UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A BASE FOR LAMPS.

SPECIFICATION forming part of Design No. 24,608, dated August 20, 1895.

Application filed July 22, 1895. Serial No. 556,826. Term of patent 3½ years.

To all whom it may concern:

Be it known that I, FRANZ YOKEL, of Meriden, in the county of New Haven and State of Connecticut, have invented a new Design 5 for a Base for Lamps, (Case E;) and I do hereby declare the following, when taken in connection with the accompanying drawing and the letters of reference marked thereon, to be a full, clear, and exact description of the same, 10 and which said drawing constitutes part of this specification, and represents a perspective view of a base for lamps embodying my design.

This invention relates to a design for a base 15 for lamps, and it consists in the configuration and ornamentation as shown in the accompanying drawing.

The upper part of the base is dome-like in shape, and between bands A and B is a scroll

and shell ornamental band C. Below the 20 band B four feet extend downward, terminating in upwardly-turned scrolls D, the legs being ornamented by a grotesque mask E and connected by an outwardly-curved scroll-shell ornamentation F, all as shown in the accompanying illustration.

I claim—

The design for a base for lamps as herein described and shown in the accompanying illustration.

In testimony whereof I have signed this specification in the presence of two subscribing witnesses.

FRANZ YOKEL.
